(57) **CLAIM**

We claim the ornamental design for reversible squatting toilet stool, as shown and described.

DESCRIPTION

FIG. 1 is a perspective view of the new design for a reversible squatting toilet stool;

FIG. 2 is a front elevation view of the design shown in FIG. 1;

FIG. 3 is a rear elevation view of the design shown in FIG. 1;

FIG. 4 is a left side elevation view of the design shown in FIG. 1;

FIG. 5 is a right side elevation view of the design shown in FIG. 1;

FIG. 6 is a top view of the design shown in FIG. 1; and,

FIG. 7 is a bottom view of the design shown in FIG. 1.

The broken lines shown in the drawings depict portions of the reversible squatting toilet stool that form no part of the claimed design.
